Primary Examiner — Darlington Ly(74) *Attorney, Agent, or Firm* — Sterne, Kessler, Goldstein & Fox P.L.L.C.(57) **CLAIM**

The ornamental design for a vehicle bicycle carrier, as shown and described.

DESCRIPTION

1.1 is a rear elevation view of a vehicle bicycle carrier showing my new design.

1.2 is a left side elevation view thereof

1.3 is a right side elevation view thereof;

1.4 is a front perspective view thereof;

1.5 is front elevation view thereof; and

1.6 is a top plan view thereof.

The broken lines in the figures show portions of the vehicle bicycle carrier that form no part of the claimed design.
